(57) **ABSTRACT**

A new and distinct cultivar of *Sansevieria aubrytiana* plant named 'CANDLELIGHT' particularly characterized by its variegated foliage with different irregular bands of light and dark, green and yellow color in the backside of the leaf blade. Supported in a rosette; 60-80 cm plant height; erect plant habit, moderate drought tolerance with low need for water and resistant to anthracnose (*Colletotrichum sansevieriae*) disease.

3 Drawing Sheets

1

Latin name of the genus and species of the claimed plant:
Sansevieria aubrytiana.

Variety denomination:

BACKGROUND OF THE INVENTION

The present invention relates to a new and distinct cultivar of *Sansevieria* plant, botanically known as *Sansevieria aubrytiana*, of the family Asparagaceae, hereinafter referred to by the cultivar name 'CANDLELIGHT'.

Sansevieria is a monocotyledonous flowering plant which can be produced in either hard-leaved or soft-leaved varieties for interior use as a house plant or outdoors ornamental plant.

The new *Sansevieria* 'CANDLELIGHT', originated from a naturally occurring mutation of the *Sansevieria* 'Lauren' (U.S. Plant Pat. No. 29,489 P2). The new *Sansevieria* 'CANDLELIGHT' was discovered and selected by the inventor, Marvin Gonzalez Villegas, as a single sprouting rare, mutation in a 'Lauren' plantation in a controlled environment in Monterrey, San Carlos, Alajuela Province, Costa Rica.

Asexual reproduction of the new *Sansevieria* cultivar by vegetative cuttings was first performed in July 2019 in Monterrey, San Carlos, Alajuela Province, Costa Rica, and has demonstrated that the combination of characteristics as herein disclosed for the new cultivar are firmly fixed and

2

retained through successive generations of asexual reproduction. The new cultivar reproduces true to type.

BRIEF SUMMARY OF THE INVENTION

The following traits have been repeatedly observed and are determined to be unique characteristics of 'CANDLELIGHT', which in combination distinguish this *Sansevieria* as a new and distinct cultivar:

1. Variegated foliage with different green tones on the irregular bands and light and dark, green and yellow colored irregular bands in the backside of the leaf blade.

2. Wide and lanceolate leaves, 60-80 cm and supported in a rosette disposition.

3. 60-80 cm plant height.

4. Plant habit: Erect.

5. Needs little water and is moderately drought tolerant.

The new variety 'CANDLELIGHT' presents an average of 4-5 leaves per plant when it reaches its maturity (between 6-10 months). The new variety has an erect growth habit, and the entire plant can reach a height between 60-75 cm. The leaves are narrow, 5-6 cm (average measured at the widest part of the mature leaf) and lanceolate with a soft waxy texture. The plant has a cylindrical shape.

The new variety is moderately drought tolerant, adapts to conditions of light and shade, and shows resistance to anthracnose (*Colletotrichum sansevieriae*) disease.

Plants of the new *Sansevieria* 'CANDLELIGHT' differ from plants of the parental cultivar, 'Lauren' (U.S. Plant Pat. No. 29,489 P2) in the characteristics described in Table 1.

TABLE 1

Comparison with Parental Varieties

Characteristic	New Cultivar 'CANDLELIGHT'	Parent 'Lauren' (U.S. Plant Pat. No. 29,489 P2)	Comparison Plant 'Yellowstone' (U.S. Plant Pat. No. 31,361 P2)
Plant Vigor Color	Less vigor (less leaves). Variegated leaves with different irregular bands and light and dark, green and yellow colored irregular bands in the backsides of the leaf blade.	More vigor (more leaves). Variegated leaves (different green tones on the irregular bands).	Less vigor (less leaves). Variegated leaves with different green tones on the irregular bands and light green tones on the stripes along the margins.
Shape	Wide and lanceolate leaves in a rosette.	Wide and lanceolate leaves in a rosette.	Wide and lanceolate leaves in a rosette.
Texture of leaves	Smooth-textured leaves, sharp, slightly sinuate margins.	Smooth-textured leaves.	Smooth-textured leaves, smooth margins.

Of the many commercial cultivars known to the present inventor, the most similar in comparison to the new *Sansevieria* 'CANDLELIGHT' is its parent, *Sansevieria* 'Lauren' (U.S. Plant Pat. No. 29,489 P2) in the characteristics described in Table 1.

BRIEF DESCRIPTION OF THE PHOTOGRAPHS

The accompanying photographs illustrate the overall appearance of the new *Sansevieria* cultivar 'CANDLELIGHT' showing the colors as true as is reasonably possible with colored reproductions of this type. Colors in the photographs may differ slightly from the color value cited in the detailed botanical description which accurately describe the color of 'CANDLELIGHT'.

FIG. 1—Shows a side view of a six-month old plant of *Sansevieria* 'CANDLELIGHT' in a 26 cm diameter pot.

FIG. 2—Shows a pot down view of a typical six-month-old plant of *Sansevieria* 'CANDLELIGHT'.

FIG. 3—Shows a close-up view of the typical leaves of *Sansevieria* 'CANDLELIGHT' from a six-month old plant (upper side—A, under side—B).

DETAILED BOTANICAL DESCRIPTION

The new *Sansevieria* 'CANDLELIGHT' has not been observed under all possible environmental conditions. The phenotype of the new cultivar may vary with variations in environment such as temperature, light intensity, and day length without any change in the genotype of the plant.

The photographs, together with the following observations, measurements and values describe the new *Sansevieria* cultivar 'CANDLELIGHT' as grown in open field conditions in Monterrey, San Carlos, Alajuela province, Costa Rica, which closely approximate those generally used in commercial practice. 'CANDLELIGHT' was grown in tropical lowlands in Costa Rica with day lengths of 12 to 13

hours and ambient temperature to 85 degrees. The level of relative humidity was 80%. No supplementary artificial light is necessary.

This crop does not require constant fertilization, to increase production per area about 200 kg ha⁻¹ N, 150 kg ha⁻¹ of P and 100 kg-ha K are required, the production is closely related with soil conditions in which they are grown.

Color references are made to The Royal Horticultural Society Colour Chart (R.H.S. 2018), except where general colors of ordinary significance are used. The photographs and descriptions were taken during the rainy season in Monterrey, San Carlos, Alajuela province, Costa Rica, with outdoor day temperatures of 24.5° C. during the day and 18° C. at night. The age of the plants described is 8 months. Classification:

Botanical.—*Sansevieria aubrytiana*.

Variety denomination.—'CANDLELIGHT'.

Parentage: *Sansevieria aubrytiana* 'Lauren' (U.S. Plant Pat. No. 29,489 P2).

Optimal growth conditions:

Light intensities.—High adaptability to outdoor or indoor conditions.

Temperature.—Day: 24° C. to 32° C. Night: 18° C. to 23° C.

Temperature tolerance.—Tolerant to a low temperature of about 12° C. and tolerant to a high temperature of about 35° C.

Fertilization.—200, 150 and 100 kg ha⁻¹ of N, P and K.

Growth regulators.—Not necessary.

Propagation:

Type.—Vegetative, by rooted cuttings.

Rooting habit and description.—Rhizomes, with short roots.

Time to initiate roots.—About 12 to 22 days at 20-25° C.

Time to produce a rooted cutting.—About 15 to 22 days at 20-22° C.

Plant:

General appearance and form.—

Height.—About 75 cm when grown in ground, about 60 cm when grown in a 26 cm size container.

Spread.—About 15 cm when grown in ground. About 12 cm when grown in 26 cm size container.

Form.—Monocot; leaf bases arranged in a rosette around growth point.

Shape.—Cylindrical.

Growth rate and habit.—About 2 cm per week; upright.

Fragrance.—None.

Stem.—Modified (rhizome and foliage) — Length: About 12 cm when grown in ground. About 8 cm when grown in 21 cm size container. Diameter: About 3.0 cm to 4.0 cm. Shape: round. Texture: rough. Color: RHS 4D. Strength: Strong and durable. Internode length: About 0.6 mm to 0.8 mm.

Foliage:

Quantity.—About 5-7 leaves.

Arrangement and attachment.—Single, alternate; leaf bases arranged in a rosette around growth point.

Leaf length.—About 30 cm.

Leaf width.—About 9 cm.

Overall shape of leaf.—Lanceolate.

Apex shape.—Acute, triangular.

Base shape.—Plane.

Margin.—Sharp, slightly sinuate.

Texture.—Upper Surface: smooth and waxy texture.
Under Surface: smooth and waxy texture.
Pubescence.—Upper Surface: none. Lower Surface: none.
Color of mature leaf.—Upper Surface: RHS 150 A 5 (vertical striations) and RHS 141 A (along the margins). Lower Surface: RHS 150 A (vertical striations) and RHS 141 A (along the margins).
Color of immature leaf.—Upper Surface: RHS 150 A (vertical striations) and RHS 141 A (along the margins). Lower Surface: RHS 150 A (vertical striations) 10 and RHS 141 A (along the margins).
Venation.—Pattern: longitudinal/parallel leaf shape. Color: none.
Leaf fragrance.—None. 15
Inflorescence description:
Arrangement and type.—Inflorescence.
Orientation at opening.—Outward orientation regarding the spile.
Quantity.—Per Plant with at least one open flower: 20 About 60 at 2 weeks.
Inflorescence size.—Length: About 35 cm. Diameter: About 1.2 cm.
Flower size.—Length: About 6 cm. Diameter: About 0.5 cm. Depth: About 0.5 cm. 25
Fragrance.—None.
Bud.—
Rate of opening.—About 7 to 8 days, according to weather.

Shape.—Ovoid.
Length.—About 2 cm.
Diameter.—About 1 cm.
Color.—Apex: RHS 149 B. Base: RHS 142 B.
Texture (both surfaces).—Smooth.
Reproductive organs:
Androecium.—Stamen: Number: 6 per flower. Length: About 1.2 mm. Color: RHS 150 D. Anther: Length: About 4 mm. Width: About 1 mm. Color: RHS 150 D. Filament: Length: About 1.3 mm. Color: RHS 150 D. Pollen: Amount: moderate. Color: RHS 150D.
Gynoecium.—Pistil: Number: One per flower. Length: About 1.5 mm. Stigma: Length: About 0.5 mm. Width: About 1 mm. Color: RHS 150 D. Style: Length: About 20 mm. Color: RHS 150 D. Ovary: Length: About 5 mm. Width: About 4 mm. Color: RHS 143 A.
Weather resistance: Moderately Drought Tolerant.
Disease/pest resistance: High resistance to anthracnose (*Colletotrichum sansevieriae*).
Disease/pest susceptibility: Not observed so far.

25

The invention claimed is:

1. A new and distinct *Sansevieria* plant named 'CANDLELIGHT', substantially as illustrated, and described herein.
